STABILIZED SPRING GROUP FOR RAILWAY CAR TRUCK

Ray C. Williams, Chicago, Ill., assignor to Standard Car Truck Company, Chicago, Ill., a corporation of New Jersey

Filed Feb. 21, 1958, Ser. No. 716,712

3 Claims. (Cl. 269—9)

The present invention relates to an improved spring group and stabilizer assembly for railway car trucks and comprises a composite assembly of load springs and cooperating friction stabilizing mechanism including a pair of friction shoes which have loose floating engagement with an upper spring follower and which are normally urged outwardly against a pair of cooperating wear plates by a single stabilizer spring with constant spring pressure.

The objects of the invention are manifold and, principal among them is the provision of a stabilizer unit for railway car trucks having associated therewith the usual load springs, together with stabilizing mechanism in the form of a pair of friction shoes and cooperating wear plates therefor wherein the friction shoes are provided with a common stabilizing spring by means of which they are urged into frictional contact with their respective wear plates with equal pressure at all times, such pressure being obtained without the use of wedges or inclined planes, thus obviating the tendency inherent in conventional stabilizer units for the friction shoes to bind unduly against the wear plates with which they are associated when the stabilizer springs are compressed beyond a predetermined degree.

Another object of the invention is to provide a stabilizer unit of this character wherein the friction shoes associated therewith are independent of the top follower plate and have sliding contact with the latter so that the normal fore and aft or lateral shifting movement of the top follower plate will not be imparted to the friction shoes on which it rests, thereby leaving the friction shoes free for their normal cooperation with their respective wear plates, whereby there will be no rocking or tilting of the shoes during any irregularities in the motion of the top follower. In other words, it is an object of the invention to provide a stabilizer unit wherein any irregular motion of the top follower will exert no stresses on the friction shoes associated therewith, whereas the friction pressure will remain constant regardless of such motion.

Another and more specific object of the invention is to provide a stabilizer unit including a bottom follower having means associated therewith for supporting a pair of wear plates in vertically disposed spaced relationship, and a top follower having means associated therewith for supporting an expandable friction shoe assembly thereon, the expandable friction shoe assembly being designed for telescopic reception between the two opposed wear plates on the bottom follower, together with means provided on the opposed wear plates whereby the expandable friction shoe assembly may automatically be initially compressed and guided into its telescopic relation between the opposed wear plates by the simple expedient of moving the two followers into vertical register with each other and thereafter applying downward pressure to the top follower to force the expandable friction shoe assembly into the confines provided for it by the opposed wear plates.

2

Numerous other objects and advantages of the invention, not at this time enumerated, will become more readily apparent as the following description ensues.

In the accompanying drawings forming a part of the specification a preferred embodiment of the invention has been shown.

In these drawings:

Fig. 1 is a vertical sectional view taken substantially centrally through a spring group stabilizer unit constructed in accordance with the principles of the present invention and showing the same operatively applied between the bolster of a railway car truck side frame.

Fig. 2 is a sectional view taken substantially along the line 2—2 of Fig. 1.

Fig. 3 is a sectional view taken substantially along the line 3—3 of Fig. 2, and

Fig. 4 is a sectional view similar to Fig. 1 illustrating the manner in which the stabilizer unit is assembled to support a railway car bolster.

Referring now to the drawings in detail, the improved spring group stabilizer unit of the present invention is designated in its entirety at 10 and is shown in the drawings as being operatively installed beneath a truck bolster 11 which extends transversely between the side frames (see Figs. 1 and 4) of a railway car truck, the bolster extending into the usual bolster openings 59 on opposite sides of the truck.

The stabilizer unit 10 involves in its general organization a top follower 12 and a bottom follower 13, between which followers there are interposed a series of composite load spring assemblies, each of which has been designated in its entirety at 14. The top and bottom followers 12 and 13 respectively are generally of square configuration in horizontal plan elevation and one of the composite spring assemblies 14 is arranged adjacent each corner of the unit while the two remaining assemblies 14 are disposed on opposite sides of the unit in the medial regions thereof and assume positions which are interposed between the adjacent pairs of units and which are offset slightly inwardly toward each other out of alignment with the adjacent pairs. The top and bottom followers 12 and 13 respectively constitute upper and lower spring plates and each is provided with marginal retaining flanges 15 to retain the coiled load spring groups 14 in position between the plates and prevent displacement thereof. The composite spring assemblies 14 are substantially identical in construction and each comprises a pair of nested helical springs including a relatively heavy outer spring 16 and a lighter concentric inner helical spring 17.

The lower follower or spring plate 13 is in the form of a casting of shallow tray-like design from which there extends upwardly in the medial regions thereof a generally rectangular wall 20 (see particularly Fig. 1) including relatively long upstanding side walls 21 and relatively short upstanding end walls 22. The side walls 21 are bowed inwardly in the medial regions thereof as at 23 (Fig. 2) to afford a clearance for the inner side portions of the two medial spring assemblies 14. The four walls, 21, 22, form in effect a generally rectangular box-like open-top casing in which there is adapted to be received an expandable friction shoe assembly designated in its entirety at 24, the nature and function of which will be set forth presently. Each end wall 22 of the upstanding wall structure 20 has secured to the inner face thereof a wear plate 25 which is secured to the inner face thereof by means of a nut and bolt assembly 26, the bolt being provided with a tapered head 27 which is counter-sunk in the plate 25. The extreme lower ends of the wear plate 25 normally rest on a shelf (see Fig. 4) which is part of wall 22, but may be attached to the bottom follower 13 by means of frangible reinforcing

welds 28 which serve to augment the clamping action of the nut and bolt assembly 27 and assist in maintaining the wear plate 25 in position on the inside surfaces of the end walls 22. The welds 28 are capable of being broken after the nut and bolt assembly 27 have been removed, thus facilitating replacement of worn wear plates. The upper edges of the wear plates 25 are flared outwardly as at 29, as best seen in Figs. 1 and 4, for purposes that will be made clear presently.

An end of the bolster is adapted to rest upon the top follower 12 in the usual manner of supporting such bolster. The upstanding circular boss 30 provides a hexagonal socket 32 which serves to confine the bolt head of a nut and bolt assembly 33, the function of which will be described presently.

The friction shoe assembly 24 includes a pair of friction shoes proper 40 and 41, the two shoes being substantially identical in configuration but being disposed oppositely in the assembled friction shoe structure. Each shoe is in the form of a generally cup-shape shell or casting including a vertical wall 42 having an outside friction surface 43 thereon designed for frictional sliding engagement with a cooperating friction surface 44 provided on each of the wear plates 25. The upper edge of the wall 42 merges with an inturned flange portion 45, the two flange portions 45 of the friction shoes 40 and 41 respectively being slidably held against the depressed medial region 46 of the top follower 12 by a bowed leaf spring 56. A pair of side webs 47 extending between the vertical wall 42 and inturned flange portion 45 serve to reinforce these latter flange portions.

As best seen in Fig. 1, the two friction shoes 41 are disposed in back to back relationship within the assembly 24, which is to say that their operative friction surfaces 43 face outwardly away from each other and are confined between the opposed wear surfaces 44 of the wear plates 25. The two shoes 40 and 41 are yieldingly spread apart, which is to say they are urged outwardly in opposite directions away from each other, by means of a spring 48, the opposite ends of which are centered on the inside faces of the vertical walls 42 of the shoes by means of inwardly extending bosses 49 which project into the spring and which are provided with central bores 50 therethrough and through which bores there slidably extends a tie rod 51. The tie rod 51 is provided with an enlarged hexagonal head 52 at one end thereof which is located within hexagonal socket 53 provided in one of the bosses 49. The other end of the tie rod 51 is threaded as at 54 and threadedly receives thereon a nut 55 which is similarly located in the hexagonal socket 53 of the opposed boss 49.

The friction shoe assembly 24, including the two friction shoes proper 40 and 41, the spring 48, and the tie rod assembly 51, is adapted to be loosely and slidably secured to the underneath face of the depressed portion 46 of the top follower 12 by means of said bowed leaf spring 56 the ends of which bears as at 57 against the underneath faces of the inturned flange portions 45 of the shoes 40 and 41, the leaf spring being centered upon the previously mentioned nut and bolt assembly 33 with the nut which is associated with such assemblies serving to draw the leaf spring 56 upwardly and create a limited amount of pressure between the leaf spring and the inturned flanges 45 at the previously designated regions 57.

The central regions of the spring 56 may be clamped against a depending circular boss 58 which surrounds the bolt assembly 33 and which is formed on the depressed region 46 of the top follower 12.

To assemble the composite friction shoe device 24, the two friction shoes proper 40 and 41 are positioned in their back-to-back relationship with the spreader spring 48 interposed therebetween and centered on the two bosses 49. The tie rod 51 is then inserted through the

bores 50 provided in the bosses 49 and the head 52 of the tie rod is pushed into the hexagonal socket 53 associated with the shoe 41. The friction shoes 40 and 41 are then moved toward each other, thus compressing the spring 48 to such a degree that the threaded end 54 of the tie rod 51 will project outwardly beyond the outer friction surface 43 of the shoe 40 so that the nut 55 may be partially threaded onto the threaded portion 54 and spring 48 is relieved so that the assembly will expand and allow the nut 55 to be pulled into the hexagonal socket 53 whereupon the shoes 40 and 41 will be urged outwardly to the extent afforded by the pre-determined distance between tie-rod head and nut, with the head and nut locked against turning by reason of their close fit in the hexagonal sockets 53.

The composite friction shoe unit 24 may be applied to the underneath side of the top follower 12 by inserting the bolt portion of the nut and bolt assembly 33 through the central opening 36 and thereafter installing the leaf spring 56 and tightening the same against the boss 58 so that the ends of the leaf spring bear against the underneath faces of the inturned flange portions 45 of the friction shoes 40 and 41 respectively.

The manner in which the friction shoe assembly 24 is brought within the confines of and inserted into the rectangular wall structure 20 is illustrated in Fig. 4. It is to be noted that the outer lower edges of the vertical walls 42 of the friction shoes 40 and 41 are chamfered as at 60 and these chamfered edges are adapted to register with mating cam surfaces 61 provided on the inclined upper edge portion 29 of the wear plates 25, which are attached to the end walls 22 of the rectangular wall structure 20 when the friction shoe assembly 24 is at its fully expanded position and when it is superimposed over the wall structure in the manner indicated in Fig. 4. A preferred method is to set the load springs in position in the bottom follower. Then bring the top follower assembly into position over the bottom follower assembly. Apply pressure by any convenient means to cause the friction shoe assembly 24 to enter between the wear plates 25 until the top follower 12 touches the tops of the load springs. The total assembly will now hold itself together and is ready to be slid into the side frame bolster window, under the upraised bolster. The bolster is then lowered into operative position on the spring group and stabilizer assembly 10.

In the operation of the stabilizer unit 10, the extent to which the friction shoe assembly 24 moves downwardly into the confines of the wall structure 20 is obviously a function of the load applied to the assembly by the bolster 11. The various load spring assemblies 14 will function in the normal manner of such load springs to assimilate the load and when the railway car is in a position of rest, the load will be balanced by the load spring assemblies and the friction shoe assembly 24 will seek a normal level within the confines of the wall structure 20 commensurate with the applied load. During travel of the railway car along a roadbed, relative movement between the top and bottom followers or spring plates 12 and 13 respectively will be resisted by the snubbing action of the two friction shoes 40 and 41 acting on the wear plates 25 under the influence of the spring 48. Since the co-engaged wear surfaces 43 and 44 of the shoes and wear plates respectively cooperate in a vertical plane, the outward force exerted by the spring 48 on the two friction shoes 40 and 41 against the wear plates 25 will remain constant in any given position of the assembly 24 within the wall structure 20.

I claim:

1. A spring group stabilizer unit for supporting an end of a truck bolster within a bolster window of a truck side frame, the said unit comprising a bottom follower adapted to be carried by the frame at a location within said window and provided with opposed friction walls, a plurality of load springs seated on the bottom follower,

a top follower provided with a bottom face seated on the load springs, a pair of oppositely facing friction shoes positioned between said friction walls and each presenting a friction surface to one of said friction walls, means for resiliently clamping both of said shoes to the bottom face of the top follower with capacity for sliding movement thereon, and a helical stabilizer spring common to and interposed under compression between said friction shoes and serving to yieldingly urge said shoes against said opposed friction walls to damp the oscillations of said load springs.

2. A spring group stabilizer unit according to claim 1 wherein each of said friction shoes includes a flat top plate portion for bearing against the bottom face of the top follower and a vertical face portion connected to the top plate portion along contiguous edges thereof and wherein the means for resiliently clamping said shoes to

the top follower is a leaf spring carried by the top follower.

3. A spring group stabilizer unit according to claim 2 wherein inwardly projecting rigidifying webs extend along and connect the lateral marginal portions of the top plate of each shoe with the vertical face portion thereof.
